UNITED STATES PATENT OFFICE

WILLIAM LINGO, OF PASADENA, CALIFORNIA

STARTING DEVICE

Application filed May 4, 1931. Serial No. 534,997.

This invention relates to starting devices for internal combustion engines and the like and has for the primary object, the provision of a shock absorber for the starter pinion to relieve the various parts of undue strain when the starter takes up the load of starting the engine and obviates the coiled spring now used for such a purpose and which has proven to be unsatisfactory due to the frequency with which such springs break and render the starter inoperative.

Another object of this invention is the provision of a cushion drive between the starter motor shaft and the starter pinion to absorb shocks and jars due to the starter pinion engaging the teeth of the fly wheel of the engine, thereby providing a device which will render efficient service over a long period of time and one which obviates manual attention.

A further object of this invention is the provision of a starting device of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation partly in section illustrating a starting device constructed in accordance with my invention.

Figure 2 is a sectional view illustrating the same.

Figure 3 is a transverse sectional view taken on the line 3-3 of Figure 2.

Figure 4 is a sectional view taken on the line 4-4 of Figure 2.

Figure 5 is an end view illustrating the driving plate as attached to the starter motor shaft and forming a part of the shock absorber means.

Figure 6 is a fragmentary plan view illustrating the device associated with a portion of a starter motor.

Figure 7 is a transverse sectional view illustrating a modified form of spring cushioning means for the shock absorber.

Referring in detail to the drawings, the numeral 1 indicates a fragmentary portion of a starter motor which usually is in the form of an electric motor while the reference numeral 2 indicates the armature shaft thereof and has its free end journaled in a bearing 3 carried by a bracket 4 forming a part of the housing of the electric motor.

A driving plate 5 is keyed to the shaft 2 as shown at 6 and is further secured to said shaft by a set bolt 7 which prevents the driving plate from moving longitudinally of the shaft. A cushion disk 8 of rubber or like material is mounted on the shaft 2 and abuts the driving plate 5 and is provided with sockets 9 to receive pins 10 carried by the driving plate for the purpose of rotating the cushion disk by the rotation of the plate 5.

An annular member 11 is mounted on the shaft 2 and abuts the cushion disk 8 and has formed therein chambers 12 divided by abutments 13 which are provided with screw-threaded sockets 14 to receive the screw-threaded ends 15 of pins 16 extending into sockets 17 formed in the cushion disk 8 for the purpose of establishing a driving connection between the cushion disk and the annular member 11. A sleeve 18 is journaled on the shaft and has formed upon one end an annular portion 19 provided with screw-threaded sockets to receive the screw-threaded extensions 20 of blocks 21 which are positioned within the chambers 12 and engage upon opposite faces thereof by coiled springs 22. The opposite ends of the coiled springs bear against the abutments 13 thus establishing a yieldable drive between the annular member 11 and the sleeve 18. The annular portion 19 of the sleeve 18 has detachably secured thereto by fasteners 23 a combined wear and closure plate 24 which closes the chambers 12 and retains the springs therein and also limits the movement of a starter pinion 24' in one direction. The sleeve 18 has formed thereon feed threads 25 to mesh with corresponding threads formed on the interior of the starter pinion 24'. The sleeve 18 has a

reduced screw-threaded portion on which is threaded a stop collar 26 located adjacent the bearing 3 for limiting the movement of the starter pinion 24' in an opposite direction.

5 As shown in Figure 2, the sleeve 18 is provided with the reduced portion received in the bearing 3.

The rotation of the shaft 2 by the motor 1 causes a corresponding rotation of the sleeve 18 through the driving plate 5, cushion disk 8, and the shock absorber means between the inner end of the sleeve and the cushion disk 8 and the rotation of the sleeve causes the pinion 24' to move endwise toward the bearing 3 for meshing the teeth thereof with the teeth on a fly wheel 27 and which constitutes a part of an internal combustion engine.

As soon as the engine starts under its own power and the stop of the motor 1, the starter pinion 24 returns to its normal position as shown in Figures 1 and 2 bearing against the wear plate 24.

The starter pinion has formed thereon an annular bead 28 adapted to have frictional contact with a cushion block 29 supported by a bracket 30 mounted on the bracket 4 for the purpose of providing a drag on the pinion to cause the same to feed forwardly of the sleeve when the latter is rotated.

20 From the foregoing description taken in connection with the accompanying drawings, it will be understood that when the pinion 24' engages the teeth of the fly wheel and the starter motor 1 takes up the action of rotating the engine, the shock absorbing means between the sleeve and shaft 2 will give so as to absorb the sudden strain on these parts and thereby permit the device to render efficient service with long life.

40 Referring to Figure 7 which illustrates a modified form of annular member 31 which has formed therein a single abutment 32 which provides a pair of chambers 33 in which are located springs 34. A block 35 carried by the sleeve 18 extends into said chambers 33 and has the opposite faces thereof engaged by the coiled springs. This form of my invention reduces the number of parts such as springs, abutments and blocks over 50 my preferred form of invention.

While I have shown and described the preferred embodiment of my invention, it will be understood that minor changes in construction, combination and arrangement of 55 parts may be made without departing from the spirit and scope of my invention, as claimed.

Having thus described my invention, what I claim is:

60 1. A starting device including a shaft of a starting motor, a feed sleeve journalled on the shaft, a starter pinion threaded to said sleeve and moved endwise by the rotation thereof to engage the teeth of a fly wheel 65 of an engine, a driving plate secured to the

shaft, a cushion disk mounted on the shaft and secured to the driving plate, and a yieldable driving means between the cushion disk and the sleeve.

2. A starting device including a shaft of 70 a starting motor, a feed sleeve journalled on the shaft, a starter pinion threaded to said sleeve, a driving plate secured to the shaft, a cushion disk mounted on the shaft and abutting the plate and having sockets, 75 pins carried by the plate and extending into the sockets, an annular member carried on the shaft, pins carried by the annular member and extending into the cushion disk and a yieldable driving connection between the 80 annular member and the sleeve.

3. A starting device including a shaft of a starting motor, a feed sleeve journalled on said shaft, a starter pinion threaded to said sleeve, a cushion disk on the shaft, a driving 85 connection between the shaft and the cushion disk, an annular member journalled on the shaft and receiving one end of the sleeve and having chambers journalled therein, abutments formed in the annular member, 90 driving means between the annular member and the disk, blocks carried by the sleeve and received in said chamber, cushioning springs between the abutments and the blocks, and a wear plate secured to the sleeve 95 for closing the chambers and forming a bearing surface for the starter pinion to engage.

4. A starting device including a shaft of a starting motor, a feed sleeve journalled on said shaft, a starter pinion threaded on said sleeve, a cushion disk journalled on the shaft, driving means between the cushion disk and the shaft, an annular member journalled on the shaft, driving means between the cushion disk and the annular member, a cushion driving means between the annular member and the sleeve, and a retarding device 100 engaging the pinion.

In testimony whereof I affix my signature.
